UNITED STATES PATENT OFFICE.

CASSIUS M. RICHMOND, OF NEW YORK, N. Y.

BURNER FOR LAMPS.

SPECIFICATION forming part of Letters Patent No. 444,854, dated January 20, 1891.

Application filed June 10, 1886. Serial No. 204,695. (No model.)

To all whom it may concern:

Be it known that I, CASSIUS M. RICHMOND, a citizen of the United States, residing in the city, county, and State of New York, have 5 invented certain Improvements in Burners for Lamps, the nature of which is fully set forth in the following specification and illustrated in the accompanying drawings.

My invention relates to that class of lamps 10 and burners for lamps generally known as the "Argand," in which circular wicks are employed and circular flames produced, air being supplied to the flame above the plane of ignition of the wick and discharged upon 15 the inner surface of the sheet of flame, and in which also deflectors are employed to spread the flame.

The object of my present invention is to 20 improve the construction and organization of such lamps, to the end, first, that combustion may be properly regulated, thereby securing a white light; second, that the lamp may be readily wicked by persons devoid of mechanical skill; and, third, that the lamp may be 25 readily adjusted as respects the parts thereof to secure the best operation and results.

My said invention consists of certain novel 30 constructions of parts and combinations of devices which are distinctly recited in the claims at the close of this specification, and I desire it to be understood that some of said improvements may be used without the others.

I will first describe all my improvements 35 in detail as organized in the best way now known to me, having reference to the accompanying drawings, in which—

Figure 1 is a vertical central section showing the position of the different parts when combined and in readiness to be attached to 40 an oil-fountain. Fig. 2 is a side view of the burner, the central air-tube and its deflectors, also the outer flanged tube, being removed. Fig. 3 is a transverse section of same through line xx of Fig. 2. Fig. 4 is an elevation of the interior parts of the burner, 45 showing an alternative construction of the air-outlet at the upper end of the central air-tube, the lower part being broken away, showing the lower part of the feed-wick in elevation, the upper part of same and the burning wick being indicated by dotted lines. Fig. 5 is a vertical central section of the al-

ternative construction of the central air-tube with a single disk, together with a brace in said tube to give strength thereto, and also 55 the stem of same with holes or perforations therein for the purpose as hereinafter explained. Fig. 6 is a transverse section of the central air-tube through line yy of Fig. 5.

Like letters refer to like parts throughout 60 the several views.

A is a collar of usual form for supporting the chimney and perforated for the passage of air to the outer wall of the circular flame 65 of the lamp.

B is the chimney.

C is a flanged tube, perforated at its lower end for the admission of air and surrounding and forming at its upper end an outer wall for the illuminating-wick. 70

D is a tube, having openings dd for the passage of air admitted through the perforations in tube C, and also openings $d'd'$ in its bottom for the passage of the feed-wick into the oil-fountain, the walls of the openings dd in D 75 forming an inclosed passage for the feed-wick below the upper end of D, where its contact with the burning wick begins.

E is a tube inclosed by and joined to D, and having openings corresponding with those d 80 d in tube D, and also having a flange e at its upper end, to which tube E the feed-wick is attached by a wire, thread, or otherwise directly underneath the flange e and is then passed down between the tubes D and E 85 through the openings $d'd'$ into the oil-fountain.

F is a ratchet-bar actuated by the ratchet-wheel F' . The ratchet-bar is inclosed by and rides in a tube G, which is square in 90 cross-section and is supported in the bottom of tube D E.

H H are carriers for raising and lowering the illuminating-wick. They are attached at their lower ends to the ratchet-bar F and at 95 their upper ends to a flanged collar H' , on which the lower end of the illuminating-wick rests.

I is a stem hollow throughout part of its length and open at its lower end, and having 100 holes i in one of its sides, wherein the teeth of ratchet-wheel F' are engaged, and by which it is raised and lowered when said stem is in position—that is, when it is inserted in the

- tube G and surrounds or straddles the ratchet-bar F, the side of I having the holes *i i* being placed next to ratchet-wheel F². Said tube G constitutes a central guide common to the adjusting connections of both the wick-raiser and deflector of the lamp and enables simple fitting and effective organization of said connections with the other parts of the lamp.
- 10 J is a tube surrounding and supported by the stem I, having openings *j j* in its lower end for the passage of air, and open and flanged at its upper or outer end, as seen at J'.
- J² is a disk supported at the upper or outer end of stem I, there being a slight space between the disk J² and the flange or disk J' for the discharge of air conveyed through tube J upon the flame when the illuminating-wick is ignited.
- 15 K is the feed-wick, which may be of ordinary candle-wicking material, and, as has been already stated, is attached at its upper end by a thread or in any other suitable manner, as indicated at *k k*, to the upper end of tube E, directly underneath the flange *e*, and the lower ends of which are passed down through the inclosed passage-ways above referred to and through the openings *d' d'* into the oil-fountain.
- 20 L is the burning or illuminating wick, the lower end of which rests upon and is supported by the flanged collar H', said collar and wick being raised and lowered as desired by means of ratchet-wheel F' and carriers H
- 25 35 H, actuated thereby. The burning-wick is secured in position by a thread or collar tied or passed around its lower end, as indicated at *l l*. It is fed or supplied with oil from the fountain by contact alone with the outer surface of the feed-wick K. The burning-wick is inclosed by the upper end of the outer tube C.
- 30 While I prefer the construction of the central air-tube as shown in Fig. 1—that is, with the two disks slightly separated from each other—yet I have obtained good results when only the upper or outer disk J² is employed, as shown in Figs. 4 and 5, since the air discharged through the outer end of the tube J is thereby guided and discharged upon the wall of the sheet of flame.
- The arrows in the drawings indicate the direction of the air-currents when the burning-wick has been ignited.
- 45 55 60 I do not broadly claim in this application a vertically-adjustable central air-tube, nor such a tube with an air-deflector, as that forms part of the subject-matter of my prior application filed in the United States Patent Office on or about February 27, 1886.
- Having thus described my invention, I desire to claim—
1. The combination, in an Argand lamp-burner, of the central air-tube, the central stem fitted to carry and support said tube
- and extending therethrough, and a deflector mounted upon the upper end of said stem above the open upper end of said tube, substantially as described.
2. The combination, with an Argand lamp-burner, of the central air-tube and deflector mounted above it, the stem carrying and supporting said tube and deflector, and a rack and pinion elevating connection for said stem, substantially as described.
3. The combination, in an Argand lamp, of the joined wick-tubes having lateral air-inlet openings leading through the inclosed vertical passage for the wick, the flanged tube fitted to said wick-tubes, having perforations in its lower end to admit air to the inlet-openings of said wick-tubes and extending upward to form the outer wall of the burner, and the perforated chimney-supporting collar fitted to said flanged tube, substantially as described.
4. In an Argand lamp, two tubes fitted together to form a vertical passage-way for the feed-wick between them and provided with lateral air-inlet openings extending through said tubes, and the inner of said tubes being extended above the outer tube, in combination with an external removable tube fitted to said outer wick-tube and provided at its lower end with air-inlet openings communicating with and feeding air to the air-inlet openings of said wick-tubes and fitted at its upper end to inclose the burning wick of the lamp and constitute the outer wall therefor, substantially as described.
5. The combination, in an Argand lamp-burner, of two tubes mounted one within the other to form a vertical passage-way for the feed-wick between them and provided with lateral air-inlet openings extending through said tubes, the inner of said tubes being extended above the outer tube to admit of fastening said feed-wick thereto above said outer tube, the burning-wick carrier mounted outside said feed-wick, and the removable tube fitted to said outer wick-tube and provided at its lower end with air-inlet openings communicating with the air-inlet openings of said wick-tubes and fitted at its upper end to inclose said burning wick and constitute the outer wall thereof, substantially as described.
6. The combination, with the wick-tubes of an Argand lamp, of a vertically-adjustable carrier for the wick, a vertically-adjustable deflector, adjusting connections supporting said carrier and deflector, and a guide common to both said connections, arranged centrally in the wick-tubes, substantially as described.

CASSIUS M. RICHMOND.
